CLAIM

The ornamental design for a card for holding earrings, as shown and described.

DESCRIPTION

FIG. 1 is a front view of a card for holding earrings showing my new design;

FIG. 2 is a right side view thereof, the left side view being a mirror image;

FIG. 3 is a rear view thereof;

FIG. 4 is a top view thereof;

FIG. 5 is a bottom view thereof;

FIG. 6 is a right-side perspective view thereof;

FIG. 7 is a front view of a second embodiment thereof, the side, rear, top and bottom views being identical to those shown in FIGS. 2-5, respectively;

FIG. 8 is a front view of a third embodiment thereof, the side views being identical to those of FIG. 2;

FIG. 9 is a rear view thereof;

FIG. 10 is a top view thereof;

FIG. 11 is a bottom view thereof;

FIG. 12 is a front view of a fourth embodiment thereof, the side views being identical to those of FIG. 2;

FIG. 13 is a rear view thereof;

FIG. 14 is a top view thereof; and

FIG. 15 is a bottom view thereof.
